UNITED STATES PATENT OFFICE.

WILLIAM K. BENEDICT, OF NEW YORK, N. Y., ASSIGNOR TO THE CO-OPERATIVE BUILDING PLAN ASSOCIATION, OF SAME PLACE.

DESIGN FOR THE EXTERIOR OF A RESIDENCE.

SPECIFICATION forming part of Design No. 19,548, dated December 31, 1889.

Application filed December 7, 1889. Serial No. 332,871. Term of patent 3½ years.

To all whom it may concern:

Be it known that I, WILLIAM K. BENEDICT, of the city, county, and State of New York, have invented and produced a new and original Design for the Exterior of a Residence, of which the following is a specification, reference being had to the accompanying drawings, forming a part thereof.

Figure 1 represents a perspective view of a residence showing my design. Fig. 2 represents a horizontal section or plan of the first story. Fig. 3 represents a horizontal section or plan of the second story.

Similar letters of reference designate corresponding parts in all the figures.

A residence embodying my design is generally rectangular in outline on the ground plan, and is surmounted with a gable roof extending widthwise of the residence and down to the top of the first story. At the front of

the residence and at one corner thereof is an octagonal bay A. At one side of the octagonal bay is a porch B. A flight of steps a leads up to the porch B.

At the side of the residence, upon the first story, is an octagonal bay C. To the rear of the octagonal bay C and at the back of the residence is a porch D.

In the second story and arising from the front slope of the roof E is an octagonal bay F, which is above the bay A. Surmounting the bay C is a balcony G.

What I claim is—

The design for the exterior of a residence, substantially as herein shown and described.

WILLIAM K. BENEDICT.
